UNITED STATES PATENT OFFICE.

WARREN F. WHEELER, OF STONEHAM, MASSACHUSETTS.

SNOW-PLOW.

SPECIFICATION forming part of Letters Patent No. 568,507, dated September 29, 1896.

Application filed May 11, 1896. Serial No. 591,028. (No model.)

To all whom it may concern:

Be it known that I, WARREN F. WHEELER, of Stoneham, in the county of Middlesex and State of Massachusetts, have invented a new 5 and useful Improvement in Snow-Plows, which will, in connection with the accompanying drawings, be hereinafter fully described, and specifically defined in the appended claims.

10 My present invention relates to improvements upon the snow-plow described in Letters Patent of the United States issued to me April 24, 1894, and numbered 518,749; and it consists in novel changes in construction 15 whereby the plow is more easily raised and lowered and guided in its practical operations, as will be hereinafter more fully set forth, and particularly pointed out in the claims.

20 In the accompanying drawings, Figure 1 is a perspective view of the plow as seen from a point to the left thereof, and shows all the changes in construction and additional devices which constitute my present invention. 25 Fig. 2 is an indirect longitudinal section taken vertically as on line Z Z, Fig. 1, and as viewed from the right of said line. Fig. 3 is a vertical cross-section taken as on line XX, Fig. 1.

The general construction of the plow is 30 substantially the same as described in my said former patent, having the two runners B and B', the runners A and A' of the inner sled being pivoted at their rear ends to the corresponding ends of the outer runners B and B' 35 by bolts C and C'. The runner B carries upon its forward end the side F of the plow, the iron share D, and the upper curved shoe D', secured to the overhanging beam E, to which is attached, at one end, the draw-bar G. The 40 plow also comprises the oblique side F', which is supported at its forward end upon runner B and at its rearward end upon runner B', and carries the hinged wing extension I. Sled B has a plank platform J, extending from runner B to runner B' over and above sled A.

45 Upon this platform are mounted the devices for spreading wing I. A long lever L is pivoted to a block L', which is bolted to the inner wall of side F, and a transverse lever M is pivoted to a block M', secured to side F'. The 50 fulcrums of these two levers rest upon the cross-planking or platform of the auxil-

iary sled A. Thus far the parts described, excepting said fulcrums, are substantially the same in construction and purpose as the like 55 parts shown in my said former patent. I will now point out and describe a change in the construction and operation of the fulcrums of these two levers, which constitutes one part of my present invention. In my former 60 patent the fulcrums consisted of fixed blocks, over which the levers acted when the plow was raised and lowered. In the present case these fulcrums consist of links L² and M². Link L² is hinged both to the lever L and to 65 the planking K on sled A, and link M² is hinged in like manner to both lever M and to the plank K'. By thus attaching to the levers and under sled movable fulcrums I 70 reduce friction and gain an advantage which greatly lightens the effort required to raise the plow, and, besides, by the connection thus made between the levers so pivoted to the plow and the cross-planking of the under sled, I accomplish, through the links thus hinged 75 to both parts, the additional purpose which was served by the chains shown and described in my former patent and am enabled to do away with the chains.

80 My other change in construction and improvement, which constitutes the chief feature of my present invention, relates to devices by which the driver of the plow may change the direction of the draft at will and thus lighten the labor of both the horse and 85 driver, and also enable the driver to make a shorter turnaround with the plow, and easier. When plowing the snow along the line of a fence, it often happens that the snow, by drifting, is deeper near the fence, and consequently 90 the horse is inclined to keep away from the fence, making it a tedious effort to keep him reined up to the proper line for the plow to follow. I overcome this difficulty in the manner and by the means which I will 95 now describe.

I employ a pair of shafts S, which I attach, as shown, to an adjustable bar T, which is pivoted to draw-bar G by the upturned end of a rod U, which passes upward through bar 100 G and bar T. This rod U also serves as a brace or support to the draw-bar and extends backward through the oblique side F' of the plow, and thence downward to runner B', to

which it is secured. Upon the opposite side of the plow a bent rod V is connected with an eyebolt in the edge of the bar T, as shown, and, extending backward, passes through a 5 curved slot W in side F and connects with a lever V', which is pivoted at its lower end to the inner face of side F. To lever V' is pivoted a short finger-lever V², which is connected by a link or hook V³ to the bent arm 10 of a locking pin or rod V⁴, which is forced downward by an incased spring. (Not fully shown, but which is inclosed at V⁵.) There is also upon the inner wall of side F an arched and notched plate Y, (more clearly shown in 15 Fig. 2,) with the notches of which the locking-pin V⁴ engages when not disengaged by grasping-lever V², and pressing it toward lever V', which action will raise the pin against the force of its spring out of the notch, as is 20 obvious from an inspection of the drawings. When the pin is thus disengaged, the lever V' may be pushed forward to or beyond another notch, which action will, through rod V, force the end of the bar T, to which the 25 rod is thus attached, forward, turning on its pivot U. This will throw the shafts S around, as indicated by the dotted lines, to the extent that the bar T is thus moved. When the lever V' is thrown forward to its 30 fullest extent, the plow may be easily turned short around. When thrown forward to the extent of one or more notches, it will permit the horse to travel in a beaten path or where the snow is of less depth than closer to the 35 fence, while the plow will guide up to the fence and into the depth of the snow, cleaning the same off the sidewalk and at the same time relieving the horse from wallowing and the driver from a tedious effort to drive him 40 in a line which he is unwilling to travel.

When pin V⁴ is interlocked with either of the notches in plate Y, then it serves to hold bar T in adjustment and gives direction to the shafts accordingly.

The lever V is handily manipulated by the 45 driver from his stand on the platform of the sled. If a pair of horses is required, a pole or single shaft may be attached to bar T, as is obvious, it being immaterial whether one or two shafts are used, so far as the action of 50 the devices for changing the direction of the draft is concerned.

I claim—

1. The combination with the body of a snow-plow of a pivoted draw-bar; a shaft or shafts 55 attached to the bar; an adjusting-rod jointed to the bar at or near one end thereof, and extended rearward therefrom and pivoted to an actuating-lever; an actuating-lever pivoted to the body of the plow and connected with 60 the rearward end of said rod; and means for locking said lever in various positions; all substantially as and for the purposes specified.

2. The combination of shafts S, attached 65 to the pivoted bar T; bar T secured to the plow; rod V secured at one end to bar T and at its opposite end to lever V'; lever V' pivoted to the side of the plow; notched plate Y secured to the side of the plow; a spring-actuated pin V⁴, carried by lever V' and arranged to interlock with plate Y; and lever V², arranged to be manipulated with lever V' so as to release the pin from plate Y; all 70 substantially as and for the purposes specified. 75

WARREN F. WHEELER.
